UNITED STATES PATENT OFFICE

HOWARD W. NESTER, OF WORCESTER, MASSACHUSETTS, ASSIGNOR TO PARKER WIRE GOODS COMPANY, OF WORCESTER, MASSACHUSETTS, A CORPORATION OF MASSACHUSETTS

ROAD CHAIR

Application filed October 20, 1930. Serial No. 489,726.

This invention relates to devices for positioning reenforcing rods or mats in a concrete structure and for definitely spacing such rods or mats from a supporting surface.

5 The invention is particularly designed for use in concrete road construction, in which reenforcing rods or mats are commonly used in the slab or layer of concrete constituting the road bed.

10 It is the general object of my invention to provide an improved road chair for such purposes and particularly to provide a road chair which will have an extended area of contact with the supporting surface, such as 15 the subgrade of a concrete road.

My invention further relates to arrangements and combinations of parts which will be hereinafter described and more particularly pointed out in the appended claims.

20 Two forms of the invention are shown in the drawings, in which

Fig. 1 discloses the invention applied to a road chair designed to support a single mat or layer of reenforcing rods;

25 Fig. 2 is a side elevation of the construction shown in Fig. 1;

Fig. 3 is a sectional plan view, taken along the line 3—3 in Fig. 2;

30 Fig. 4 is an end view, looking in the direction of the arrow 4 in Fig. 2;

Fig. 5 is a perspective view showing my invention embodied in a construction designed to support two layers of reenforcing rods in spaced relation from a supporting surface and from each other;

35 Fig. 6 is a side elevation of the construction shown in Fig. 5;

Fig. 7 is an end view, looking in the direction of the arrow 7 in Fig. 6; and

40 Fig. 8 is a sectional plan view, taken along the line 8—8 of Fig. 6.

Referring first to Figs. 1 to 4, I have shown my improved road chair as comprising a continuous piece of wire W, bent to a desired shape and mounted upon a flat disc or plate 10. The wire W comprises an upright member 12 which is bent laterally at its lower end, as indicated at 13, to provide a foot portion adapted to be spot-welded or otherwise permanently secured to the plate 10.

The upper part of the upright portion 12 is also bent laterally, as indicated at 15 (Fig. 4), and is then bent downward and further extended laterally at 16, after which it is bent rearward and upward, as indicated at 17. 55

The rear end of the portion 17 is then bent sharply upward to form an upper loop 18, then downward to form a lower transverse loop 19, and again upward to form a second upper loop 20.

60 My improved road chair is shown in assembled relation with a pair of reenforcing rods A and B in Fig. 1. The upper rod B extends under the loops 18 and 20 and overlies the rod A which extends through the transverse loop 19 and rests upon the offset portion 16 previously described.

65 The rods A and B are thus firmly secured in position and are also definitely spaced from the surface engaged by the disc or plate 10. The disc 10 provides an extended area of contact with the supporting surface so that the vertical position of the reenforcing mat is not effected by slight irregularities in the sub-grade. Furthermore, the device takes 70 the place of the usual tie clip, otherwise used.

75 In Figs. 5 to 8, I have shown my improvements embodied in a road chair adapted to receive and position two spaced layers of reenforcing rods or mats. In this construction 80 also each improved road chair comprises a piece of wire X and a plate or disc 30. The wire X has an upright portion 31 offset at 32, to provide a seat for a lower reenforcing rod C.

85 At its lower end, the upright portion 31 is bent laterally, as indicated at 33, and this portion 33 is permanently secured to the disc or plate 30 in any suitable manner, as by spot-welding.

90 At its upper end, the upright portion 31 is provided with an upper loop 36, a transverse lower loop 37, and a second upper loop 38, which latter loop in the usual construction may be left incomplete.

95 The end of the lower offset portion 33 is reversely bent, as indicated at 40 (Fig. 8), and is extended rearward and upward, as indicated at 41 (Fig. 6), the extreme rear end of the portion 41 being provided with a 100

transversely and downwardly directed hook-like end 42.

In the drawings, I have shown this form of my improved chair assembled with lower reenforcing rods C, D, and upper rods E and F. The lower rod C rests in the offset portion 32, as previously stated, and supports the second rod D of the lower reenforcing layer. The rearwardly extended hook-like portion 42 overlies the rod C, as indicated in Fig. 5, and prevents rocking of the chair in one direction. The rods C and D are preferably held in assembled relation with the road chair by a tie clip T, which may be of a usual commercial construction.

The rod E of the upper reenforcing structure is supported by the transverse loop 37 and in turn supports the upper rod F which underlies the loops 36 and 38. While the rearwardly extended portion 42 prevents rocking of the road chair in one direction, it will be noted that the transverse loop 37 similarly prevents rocking of the chair in the opposite direction.

The rearwardly bent portion 40 is preferably slightly inclined upwardly and spaced from the disc 30, as indicated in Fig. 6, so as to provide increased resilience for the rearwardly extended member comprising the parts 40, 41 and 42.

With this form of the invention, as in that previously described, the plate or disc 30 provides an extended area of contact with the sub-grade or supporting surface, and accurate spacing of the reenforcing mats from the supporting surface is facilitated.

Having thus described my invention and the advantages thereof, I do not wish to be limited to the details herein disclosed, otherwise than as set forth in the claims, but what I claim is:—

1. A road chair comprising a substantially flat sheet metal base of extended area and a single piece of wire having a foot portion permanently and rigidly secured to said base, said wire extending upwardly from said base and having portions bent to engage and position a plurality of reenforcing members supported thereby.

2. A road chair comprising a substantially flat sheet metal base of extended area and a single piece of wire having a foot portion permanently and rigidly secured to said base, said wire extending upwardly from said base and having portions bent to engage and position a plurality of reenforcing members supported thereby, and said members being arranged in vertically spaced planes.

3. A road chair comprising a substantially flat sheet metal base of extended area and a single piece of wire having a foot portion permanently and rigidly secured to said base, said wire having an upwardly extending portion at one end of said foot portion bent to engage and position a plurality of reen-

forcing members supported thereby, and said wire at the opposite end of said foot portion being bent rearwardly and upwardly and being provided with an offset hook adapted to overlie one of said reenforcing members and to thereby prevent rocking of the road chair in one direction.

In testimony whereof I have hereunto affixed my signature.

HOWARD W. NESTER.
